PORTABLE PICKLING MACHINE

Robert C. Hopkins, Alliance, Ohio

Application May 6, 1949, Serial No. 91,820

4 Claims. (Cl. 51—164)

1

The invention relates to pickling machines, and more particularly to a portable pickling machine for pickling small stampings, castings, forgings and other articles which require cleaning with a sulphuric or other acid solution.

Under present practice several handlings are required, in the pickling or cleaning of such articles, between the press or other machine in which the articles are produced and the galvanizing pot or other station to which the pickled and washed articles are delivered, requiring additional time, labor and expense in the rehandling of the articles between operations.

The present invention contemplates the provision of a portable pickling machine which will eliminate this unnecessary handling of such articles, thus decreasing the cost of production. This machine comprises a bail or lifting beam within which is journaled a bucket for containing the articles to be pickled, the bail having integral supports extending below the bucket for contact with a floor or other bottom of a pickling or washing tank, or other horizontal support, with means for holding the bucket against rotation during transportation and means for rotating the bucket in the pickling and washing tanks.

With this construction the portable pickling machine may be placed at a press, or other machine of last operation upon which the articles are produced, and with the bucket locked against rotation and the cover thereof open, it may be filled with the articles as they are discharged from the press or the like, after which the cover may be closed and locked and the portable pickling machine transported by a crane, engaging the bail, the machine being deposited upon the bottom of a pickling tank and the bucket rotated to tumble the articles within the pickling solution, after which the machine may be lifted by a crane and deposited in a washing tank where the rotation is repeated.

After the washing of the pickled articles, the machine may be transported by a crane to a galvanizing pot, or other station, where the bucket may be dumped, depositing the pickled and washed articles without requiring handling throughout the entire series of operations.

It is therefore an object of the invention to provide a portable pickling machine comprising a perforate bucket journaled in a combined bail or lifting beam and support frame adapted to support the bucket above a horizontal supporting surface in position that it may be rotated.

Another object is to provide such a portable pickling machine having means for locking the bucket against rotation.

A further object is to provide a pickling machine of this character having means for rotating the bucket within a pickling tank or the like.

A still further object is to provide means for

producing intermittent rotation so as to produce a series of impulses or intervals between stopping and starting of the rotation so as to increase the agitation of the articles as they are tumbled within the bucket.

Another object is to provide a rotary bucket of rectangular or cubic section in order to produce the greatest displacement of the articles as they are tumbled, causing them to rub over and against each other, removing the scale, dust and the like by the simple mechanical action.

A further object is to provide a rotary pickling machine of the character referred to in which the bucket is provided with hinged covers having novel means for normally locking them in closed position.

A still further object is to provide such a pickling machine in which the articles within the bucket will have a one hundred per cent contact with the acid solution during the pickling operation.

Still another object is to provide a portable pickling machine of this character in which an intermittent, rotary motion may be imparted to the bucket by either manual or mechanical means.

The above and other objects, apparent from the drawings and following description, may be attained, the above described difficulties overcome and the advantages and results obtained, by the apparatus, construction, arrangement, combinations, sub-combinations and parts which comprise the present invention, a preferred embodiment of which, illustrative of the best mode in which applicant has contemplated applying the principle, being set forth in detail in the following description and illustrated in the accompanying drawings, in which:

Fig. 1 is a side elevation of a portable pickling machine embodying the invention, parts being broken away for the purpose of illustration;

Fig. 2 an end elevation of the improved portable pickling machine with parts broken away;

Fig. 3 a fragmentary, detail, sectional view of the means for locking the hinged covers of the bucket in closed position;

Fig. 4 a section on the line 4—4, Fig. 3.

Referring now particularly to the embodiment of the invention illustrated in the accompanying drawings, in which similar numerals refer to similar parts throughout, the improved portable pickling machine includes a combined bail or lifting beam and supporting frame comprising the two similar A-frames 10 and 11 each having a journal bearing 12 at its apex and a vertical extension 13 above the A-frame.

The lower portions of the legs 14 of the A-frames are preferably connected together by cross members in the form of channel bars 15, riveted to the legs of the A-frames as at 16.

A cross head 17 is connected to the upper ends of the upright extensions 13 of the frames as by bolts 18 located through the boss 19 at opposite ends of the cross head and through the inturned flanges 20 at the upper ends of the extensions 13, this cross head together with the extensions 13 forming a bail or lifting beam.

An eye 21 is formed at the center of the cross head 17 for engagement by the usual hook or other attaching means upon a crane whereby the machine may be lifted bodily and transported from place to place as desired.

A bucket, indicated generally at 22, is provided for containing the small articles to be pickled and is preferably of rectangular shape, being substantially in the form of a hollow cube as shown in the drawings.

Trunnions 23 are provided on opposite sides of the bucket, at the center thereof and are journalled within the bearings 12 of the frame members. The bucket is of such size that it may be rotated upon these trunnions when the A-frames 10 rest upon the bottom of a tank, or other horizontal support.

The bottom wall 24 of the bucket is perforated, as indicated at 25, and similar perforations 26 are preferably provided in all of the side walls of the bucket, covering about the lower one-third thereof.

Covers 27 are hinged upon the top of the bucket, as at 28, and are adapted to be locked in closed position during operation of the machine by any suitable means such for instance as shown in Figs. 3 and 4.

For this purpose projections or lugs 29 may be formed upon the opposed edge portions of the covers, adjacent to each side thereof and the adjacent edge portions of the covers may be notched as indicated at 31. A T-head bolt 31 is rotatably connected to each corresponding side wall 32 of the bucket and extended through the notches 30 in the covers.

This bolt is rotatably mounted between two spaced pairs of ears 33, formed or mounted upon the adjacent side wall 32 of the bucket, bolts 34 being located through the outer portions of these ears to retain the T-head bolt therein, and shoulders 35 are formed upon the lower end and upon an intermediate portion of the T-head bolt 31 for engaging the lower sides of the ears, as shown in Fig. 3.

With the cover closed, the T-head bolt 31 is turned so that the T-head 36 thereof engages over both of the lugs 29, and it will be seen that the cover will be held locked in closed position. To unlock the covers so that they may be opened to place articles within the bucket or remove them therefrom, the T-head bolt is turned at right angles so that the T-head 36 thereof will be received in the notches 30 of the covers as they are opened.

For the purpose of rotating the bucket upon the stand, a ratchet wheel 37 is fixed upon one of the trunnions 23 of the bucket and may be further attached to the adjacent side wall of the bucket as by pins 38. A lever 39 may be provided for manually rotating the bucket, this lever being fulcrumed at its lower end by means of the shaft 40 journalled in an ear 41 upon the adjacent upright extension 13 of the supporting frame.

Upon the inner end of the shaft 40 is fixed a rocker arm 42, having a pawl 43 pivoted at its lower end as indicated at 44, and a pawl 45 pivoted at its upper end as indicated at 46.

With this construction the ratchet wheel 37, and the bucket to which it is attached, may be rotated in the direction of the arrow shown on Fig. 2 with each movement of the lever 39 in either direction.

This provides an intermittent rotation of the bucket by a series of impulses, as there is an interval between stopping and starting of each rotation which will have the effect of increased agitation among the parts within the bucket, and since the bucket is of rectangular shape a hammering effect is produced which continuously dislocates the position of each article within the bucket from the outside toward the center of rotation, producing a constant displacement of the articles which rub over and against each other, removing the scale, dust, etc. by the simple mechanical action.

Although two pawls are shown for engagement with the ratchet wheel, it should be understood that either of these pawls may be eliminated so that the bucket will only be rotated during the movement of the lever 39 in one direction and will come to a stop during the movement of the lever in the opposite direction.

If it is desired to rotate the bucket mechanically rather than manually, any suitable motive means may be provided for operative connection to the lever 39. For this purpose in Fig. 1 a fluid cylinder 47 is shown supported as at 48 upon an ear 49 formed upon the upper portion of the adjacent upright extension 13 of the frame.

The piston rod 50 of this cylinder is shown as 35 pivotally connected at 51 to one end of a link 52, the other end of which is pivotally connected as at 53 to the lever 39. With this construction, as the piston rod 50 is moved downward out of the cylinder, the upper ends of the lever 40 39 and rocker 42 will be swung to the right, as viewed in Fig. 2, the pawl 45 engaging the teeth of the ratchet wheel 37 and rotating it in a clockwise direction, while the pawl 43 rides backward over the teeth of the ratchet wheel.

Then as the piston rod 50 moves upward, the lever 39 and rocker arm 42 will be swung in the opposite direction, the pawl 43 engaging the teeth of the ratchet wheel and again rotating it in clockwise direction, while the pawl 45 will ride backward over the teeth of the ratchet wheel.

For the purpose of holding the bucket against rotation during the time that it is being loaded or transported, any suitable latching device may be provided. For this purpose a latch 54 is shown in Fig. 1, pivoted upon the adjacent extension 13 of the frame, as at 55, and adapted to engage in a notched lug 56 upon the adjacent side wall of the bucket. A depending angular handle 57 may be formed upon the latch 54 for manually operating the same.

In the operation of the improved pickling machine, the bucket may be locked against rotation by the latch 54 and may be transported by a crane to a position adjacent to a press or other machine of last operation in which the articles to be pickled are made. The T-head bolts 35 are operated to unlock the covers so that they may be opened and the bucket may be so positioned that the articles may be discharged by gravity from the press or other machine directly into the bucket.

When a sufficient load has been placed within the bucket the covers are closed and the T-bolts 31 operated to lock them in closed position and 75 the pickling machine is transported by a crane

and lowered into a pickling tank the legs 14 of the A-frames resting upon the bottom of the tank so that the entire load of articles within the bucket are submerged below the level of the pickling solution.

The latch 54 is then unlocked and the bucket is intermittently rotated by the mechanism above described, tumbling the articles in the bucket against each other, within the pickling solution, until the pickling operation has been completed. 10

The pickling machine may then be transported by a crane to a washing tank and lowered therein and the bucket again rotated until the pickled articles therein are thoroughly washed, after which the pickling machine may be transported by a crane to a galvanizing pot or other station, where the covers of the bucket may be opened and it may be tilted to dump the articles so that it is not necessary to handle any of the articles during the entire series of operations.

It should be understood that all of the parts of the improved portable pickling machine should be made of suitable acid resisting metal so that the machine may be entirely submerged within the pickling solution without serious damage thereto.

According to the provisions of the patent statutes, I have explained the principle of my invention and described one embodiment thereof, but I desire to have it understood that within the scope of the appended claims, the invention may be practiced otherwise than as specifically illustrated and described, the invention residing in the provision of a portable pickling machine having a rectangular, rotatable, perforate bucket for containing the articles to be pickled and having the combined supporting frame and bail or lifting beam whereby it may be supported upon the bottom of a tank and may be easily transported from one station to another.

I claim:

1. A portable pickling machine comprising a combined supporting frame and bail, a rectangular bucket journalled in the frame in such position that when the frame rests upon a horizontal surface the bucket may be freely rotated in the frame above said horizontal surface, a ratchet wheel fixed to the bucket, a lever fulcrumed upon the frame, and a pawl upon the

lever engaging the ratchet wheel for rotating the bucket.

2. A portable pickling machine comprising a combined supporting frame and bail, a rectangular bucket journalled in the frame in such position that when the frame rests upon a horizontal surface the bucket may be freely rotated in the frame above said horizontal surface, a ratchet wheel fixed to the bucket, a lever fulcrumed upon the frame, and pawls upon the lever above and below the fulcrum thereof engaging the ratchet wheel for rotating the bucket.

3. A portable pickling machine comprising a combined supporting frame and bail, a bucket journalled in the frame in such position that when the frame rests upon a horizontal surface the bucket may be freely rotated in the frame above said horizontal surface, a ratchet wheel fixed to the bucket, a lever fulcrumed upon the frame, a pawl upon the lever engaging the ratchet wheel, a prime mover upon the frame and means connecting the prime mover to the lever for rotating the bucket.

4. A portable pickling machine comprising a combined supporting frame and bail, a bucket journalled in the frame in such position that when the frame rests upon a horizontal surface the bucket may be freely rotated in the frame above said horizontal surface, a ratchet wheel fixed to the bucket, a lever fulcrumed upon the frame, a pawl upon the lever engaging the ratchet wheel, a fluid cylinder upon the frame, a piston rod in the cylinder and means connecting the piston rod to the lever for rotating the bucket.
